UNITED STATES PATENT OFFICE

PAUL O. DIEDERICHS, OF CHICAGO, ILLINOIS, ASSIGNOR, BY MESNE ASSIGNMENTS, TO
AMERICAN MACHINE & FOUNDRY COMPANY, OF NEW YORK, N. Y., A CORPORATION
OF NEW JERSEY

ROLLER MILL

Application filed April 26, 1928. Serial No. 272,968.

This invention relates to roller mills and more particularly to an improvement in guide plates such as used on roller mills used for grinding ink and other material, 5 the guide plates serving with the upper adjacent surface portions of a pair of cooperating rolls, to form a hopper for confining a quantity of the material to be ground and to limit the grinding operation to a predetermined portion of the rolls.

The objects of the invention are; to provide an improved mounting for one or more guide plates whereby the same may be adjusted vertically to an elevated position 15 wherein cleaning of the guide plates is facilitated; to provide means for mounting a pair of guide plates, which are spaced apart lengthwise of the rolls, whereby the guide plates may be simultaneously adjusted vertically; to provide means for effecting such adjustment with a relatively quick movement; to provide means for temporarily maintaining the guide plates in elevated position of adjustment to permit the same to be cleaned with the greatest facility and in general, to provide an improved guide plate mounting and adjusting structure.

Other objects and advantages of the invention will be understood by reference to the following specification and accompanying drawing in which I have illustrated a part of a roller mill embodying a selected form of my invention.

In the drawing:

Fig. 1 is an end elevation of a part of the receiving end of a roller mill, a part being broken away and shown in section to more clearly illustrate the invention, and

Fig. 2 is an end elevation showing a part 40 of the right hand end of Fig. 1.

Referring now to the drawing, I have indicated the opposite side frame portions of the main frame of a roller mill at 10 and 11, in which side parts a plurality of cooperating 45 grinding rolls are rotatably mounted.

For the purpose of the present application, I have shown two of the cooperating grinding rolls, one being indicated at 12 and the other at 13. The roll 13 is rotatably mounted 50 at its opposite ends in upstanding frame por-

tions such as 14 of the side frames 10 and 11, and the roll 12 is preferably rotatably mounted at its opposite ends in bearing blocks such as 15, which are horizontally adjustably mounted in suitable ways provided in the respective side frames. A coiled compression spring 16 is interposed between the upstanding frame portions 14 and adjustable bearing blocks 15 to normally urge the bearing block 15 and roll 12 to move away 55 from the upstanding frame part 14 and the roll 13 respectively. A frame part or bar shown at 17, is secured to each of the side frames at convenient places and serves with any other suitable part to form the ways in 60 which the bearing blocks 15 are adjustably mounted.

The rolls 12 and 13 constitute the receiving rolls of a roller mill. A pair of guide plates 18 and 19 having their lower edges 70 shaped as shown at 20 and 21, to fit the curvature of the adjacent upper surface portions of the cooperating rolls, serve with the said adjacent surface portions to form a trough or hopper for holding a quantity of material 75 to be ground. The guide plates preferably rest or are seated on the said adjacent upper surface portions so as to form a tight joint therewith whereby fluid material such as ink may be supplied to the mill and will be effectively confined between the guide plates 80 18 and 19, which constitute the end plates of the hopper.

The guide plates 18 and 19 are pivotally and horizontally adjustably mounted on a 85 rod or shaft 22, each of the said guide plates 18 and 19 being provided with bosses 24 and 25 respectively, which are apertured as shown at 26 and 27 respectively to fit over the shaft 22. Set screws 28 and 29 threadedly engaging suitable apertures in the bosses 24 and 25 are provided for locking the guide plates in the desired position of horizontal adjustment on the shaft. It will be understood that by shifting the guide plate 18 and 19 or both of them along the shaft 22, the material to be ground will be caused to pass between predetermined limited portions of the lengths 90 of the cooperating rolls.

The shaft 22 is vertically adjustably 100

mounted in suitable supports or brackets 30 and 31 which are mounted and extend upwardly from the frame part 17 adjacent opposite ends of the cooperating rolls 12 and 13. The brackets 30 and 31 are each provided with a forked upper end portion having a way 32 between the forked arm portions and in which ways, bearing blocks such as 33 are mounted so as to be vertically adjustable. The bearing blocks 33 are preferably square, or at least provided with opposite flat side portions engaging the straight vertical inner faces of the forked arm portions of the brackets and the said bearing blocks are apertured to rotatably receive the adjacent ends of the shaft 22.

The ends of the shaft preferably project beyond the outer end of the respective bearing blocks, and pinion gear members such as 34, are secured in any suitable manner to the ends of the shaft so as to rotate therewith. In the present instance I have shown the pinion gears 34 as being provided with hub portions having suitable apertures for receiving pins such as 35, which also extend through apertures in the shaft, thereby to cause the pinion gears and shaft to rotate together.

Rack bars such as 36, are secured to one of the arm portions of each of the forked brackets so as to mesh and cooperate with the pinion gears 34. It will be readily understood that by rotating the shaft 22 and pinion gears 34, the gears will be caused to climb up on the racks and thereby elevate the shaft 22, the bearing blocks 33 sliding upwardly in the ways between the arm portions of the respective forked brackets. Any suitable means may be provided for effecting rotation of the shaft 22 and pinions 34. In the present instance, I have provided a crank 37 having a square socket 38 adapted to fit over a squared end portion 39 of the shaft 22. It will be apparent that by turning the crank 37, the shaft 22 and pinions 34 will be rotated in unison and that both ends of the shaft 22 will be elevated in unison. Obviously, if the guide plates 18 and 19 are locked in position on the shaft 22 by means of the set screws 28 and 29, the said set screws should be loosened before attempting to rotate the shaft and pinions.

Any suitable means may be provided for locking or temporarily maintaining the shaft 22 and guide plates in elevated position of vertical adjustment. I may provide some suitable disengageable means for normally preventing backward rotation of the shaft 22, i. e., rotation in the direction necessary for lowering the shaft, but in the present instance, I prefer to provide pins such as shown at 40, which are adapted to be passed through apertures 41 provided in the arm portions of the respective brackets. The apertures 41

are located adjacent the upper ends of the arms in position to support the shaft in the desired position of vertical adjustment, the pins being adapted to be inserted through the apertures underneath the respective bearing blocks 33. I prefer to attach the pins 40 to the respective brackets by means of chains such as shown at 41 to prevent the pins from being lost and to maintain the pins in position where they are handy for use when desired.

When the mill is used for grinding ink or the like, some of the ink works its way between the adjacent edges of the guide plates and surface portions of the rolls. When it is desired to use the mill for grinding a different color of ink, or when the operation of the mill is to be stopped for any extended length of time, it is desirable that all ink adhering to the operating parts of the machine be cleaned therefrom. It will be understood that in a machine embodying the above described guide plate mounting features, such cleaning is readily accomplished since the guide plates which normally are very heavy in weight can easily and quickly be adjusted to elevated position. The position of elevation in which the shaft is adapted to be supported by means of the pins 40 is preferably such that the guide plates may be swung clear of the rolls, about the shaft 22 on which they are pivotally mounted. Thus cleaning of the guide plates and also of the rolls is greatly facilitated.

I am aware that changes may be made in the form, construction and arrangement of parts without departing from the spirit of the invention, the scope of which should be determined by reference to the following claim, which should be construed as broadly as possible consistent with the state of the art.

I claim as my invention:

In a roller mill, the combination of a main frame, a pair of cooperating rolls mounted on said main frame, a pair of brackets extending upwardly from said main frame respectively adjacent the opposite ends of said pair of rolls, a shaft vertically adjustably mounted in said brackets, a pair of guide plates pivotally mounted on said shaft, depending therefrom and serving with the adjacent upper surface portions of said rolls to form a hopper for holding material to be ground, and means for effecting vertical adjustment of said shaft to an elevated position permitting said plates to be swung about said shaft to a position facilitating cleaning of the guide plates, said means comprising a pair of racks respectively mounted on said brackets, a pair of gears secured to said shaft and respectively meshing with said racks, and a crank for effecting rotation of said shaft and gears.

PAUL O. DIEDERICHS.
